BITUMINOUS MATERIALS AND PROCESS OF
MAKING SAMEAlfred R. Ebberts, New York, N. Y., assignor to
Colprovia Roads, Inc., New York, N. Y., a cor-
poration of New YorkNo Drawing. Application September 19, 1930
Serial No. 483,126

42 Claims. (Cl. 106—31)

This invention relates to bituminous binding materials such as are used as binders for stone aggregate in road construction. It not only is applicable to bitumens of relatively high melting point which may, for example, be applied in powdered form, but is also applicable to relatively low melting point bitumens such as flux oils.

This invention is particularly applicable to a process wherein a bitumen of high melting point gradually amalgamates with a bitumen of relatively lower melting point without the application of heat and at ordinary temperatures to produce a substantially homogeneous binder of desired melting point. Thus this invention is applicable to and improves upon a process of road construction wherein aggregate material is first coated with a substantially non-volatile flux oil which is liquid at temperatures below summer heat and then is coated with powdered bitumen having a melting point higher than is necessary to resist summer heat which adheres to the first coating as an exterior dustlike coating to produce a material the particles of which do not stick together during storing and laying due to the dustlike character of the exterior coating, but which when laid and consolidated in place become securely and permanently bound into a semi-rigid mass by the gradual amalgamation of the liquid and solid binders upon rolling and subsequent traffic to form a substantially homogeneous binder having a melting point sufficiently high to resist summer heat.

Heretofore in the process of road construction referred to, difficulties have been encountered because of failure of the binder parts to properly amalgamate the one with the other and form a proper binder. Difficulties have also been encountered in properly powdering high melting point bitumens. These and other difficulties will be discussed more fully hereinafter.

It is a feature of this invention that individual relatively low melting point bitumens such as flux oils and powdered bitumens of relatively high melting point are not only improved in themselves for purposes for which they are intended but also are improved so that they will blend and amalgamate the one with the other in an improved manner producing an amalgamated binder of superior nature.

Further features of this invention are that a process of making a high melting point bitumen may be controlled so that the resulting product may be made to flux and amalgamate at desired rate with a particular flux oil and that a process of making a flux oil may be controlled so that

the resulting product may be made to flux and amalgamate at desired rate with a particular high melting point bitumen. Moreover, it is a feature of this invention that flux oils and high melting point bitumens may be produced which may be made to amalgamate at proper rate with bitumens, either hard or soft, occurring in bituminous rocks.

It is an advantageous feature of this invention in connection with the application of binder parts in the process of road construction above referred to, that a high melting point bitumen may be produced which, when applied as a powder without the application of heat, to aggregate particles coated with a flux oil, will be soluble to the proper extent and at the proper rate in the flux oil, so that during mixing and laying the two parts will not amalgamate too rapidly and prematurely to form unworkable masses which cannot be removed from the mixer or handled or laid cold but will remain substantially unamalgamated, the powdered bitumen acting as a separating substance keeping the individual aggregate particles from adhering to each other and freely movable with respect to each other, and so that after the mix is laid and consolidated with pressure in place the two parts will nevertheless amalgamate and flux together to produce a strong and substantially homogeneous binder. Moreover, it is an advantage of this invention that a high melting point bitumen may be made which, in addition to the properties above mentioned, is sufficiently hard and brittle to permit grinding and reduction to a powder without the formation of lumps or unworkable masses during grinding. According to this invention, high melting point bitumen can be produced which may be readily ground to desired fineness by simple economical means producing a friable powder and which is also of such solubility that it will amalgamate at proper rate with a flux oil used in conjunction therewith.

Hard bitumens have heretofore been made from distillation residues which remain after the lighter fractions have been removed and which have a consistency ranging from liquids to semi-solids of about 200 penetration or melting below 100° F. by blowing such residues, thus raising the melting point of the residues to about 300° F. as determined by the ring and ball method. This product is known as mineral rubber and while useful for certain purposes, its use in road making of the type referred to above is fraught with great difficulties. Mineral rubber is defective first because, due to its rubbery nature, it tends

to form into unworkable lumps or masses when attempt is made to reduce it to a powder, and secondly because it is not sufficiently soluble in many flux oils to secure proper amalgamation in the finished road. Lesser blowing, while it reduces the melting point somewhat, thus making the material more soluble, has been found to increase the rubbery consistency of the material, thus making it unfit for grinding. Increased blowing, on the other hand, while it lowers the rubbery consistency of the material, has been found to increase the insolubility of the material in flux oil, thus making it unfit as a binder ingredient.

15 According to this invention, bituminous material which is to be blown to a high melting point can be treated prior to blowing either to remove certain of the substances which cause the final blown material to be rubbery, or by adding to the material another material which because of its composition contains materials which, when blown, tend to reduce the rubbery consistency of the final product. Preferably a combination of the two methods of reducing the rubbery consistency of the final product is employed. Moreover, I have found that the rubbery consistency of the blown material can thus be reduced not only without increasing the insolubility of the material but also with attendant decrease in insolubility where desired, thus producing a material which can be readily ground to a powder and which also amalgamates with a flux oil at the desired rate.

Instead of directly blowing straight run residues ordinarily encountered having, for example, melting points below 100° F., to high melting points such as 300° F. as heretofore practiced, I have found that certain constituents which cause the blown product to be rubbery can be removed 35 as by straight distillation as with steam up to a point where the residue will have a comparatively high melting point such as 170° F. If this material is then blown to about 240°-270° F., a satisfactory final product will be obtained which 40 can be readily reduced to a powder and which will amalgamate properly with the flux oil. Moreover, I have found that certain materials contain substances which, when blown, increase the brittleness and grinding quality of blown materials with which they are mixed while at the 45 same time tending to increase their solubility. An example of such a material is cracking still residue, which material is advantageous for use according to this invention because it is efficient 50 and readily available and cheap. While certain advantages can be obtained according to this invention merely by mixing cracking still residue with straight run residue and then blowing the mixture to a high melting point, it is preferable 55 to first to make the mixture and then treat the mixture as by straight running with steam prior to blowing as a superior product can be obtained in this way. Where the mixture is used, however, the straight running with steam does not have 60 to be taken to so high a melting point as where cracking still residues are not used in order to produce an entirely satisfactory product. By such procedure, a product which is hard and brittle and therefore readily powderable will be 65 produced and at the same time the solubility of the bitumen may be modified so as to make it soluble at a desired rate in a flux oil to be used in conjunction therewith.

By way of illustration, where straight reduction residues of approximately 800 sec. furol vis-

cosity are available, this material when directly blown results in a binder which is too rubbery for grinding or too insoluble for use or both, depending upon the amount of blowing to which it has been subjected. These difficulties can be overcome according to this invention by straight running such residues with steam so that a residue having a melting point of about 170° F. is produced. Straight running may be carried out in any type of still commonly used for the purpose. When this product is blown to a melting point of from 240-275° F., I have found that a product of the desired hardness and solubility is obtained. Any type of blowing still commonly used such as a tank or tower still may be used for carrying out the blowing operation. A type of blowing still which has proved to be satisfactory is a vertical cylindrical insulated tower with radial air inlets having orifices on the sides thereof to produce swirling. According to common practice, the air may be controlled to maintain a temperature around 450-600° F. and when the operation is complete the material is allowed to stand hot for five hours or more to permit escape of air and water vapor.

Since the straight distillation is relatively expensive compared with blowing, I have found it desirable to mix with the initial distillation residues a certain amount of cracking still residues. Where, for example, 35 parts of the straight reduction residues of about 800 sec. Furol viscosity are mixed with 65 parts of cracking still residues of about 400 sec. Furol, this mixture, due to the presence of the cracking still residues, need only be straight run to a melting point of about 140° F. prior to blowing, and when blown to a melting point of 240-275° F. produces a completely satisfactory hard bitumen.

The following table will indicate variations in treatment of different mixes according to this invention.

Straight reduction residues	Cracking still residues	Straight reduction melting point (M. P.)	Blowing melting point (M. P.)
100% (any viscosity).	0%.	170° F. M. P.	240-275° F. M. P.
65% (800 sec. Furol).	35% (400 sec. F.).	160° F. M. P.	240-275° F. M. P.
35% (800 sec. Furol).	65% (400 sec. F.).	140° F. M. P.	240-275° F. M. P.
20% (41-50 penetration).	80% (400 sec. F.).	120° F. M. P.	240-275° F. M. P.
0%.	100% (any viscosity).	300° F. flash point.	200-275° F. M. P.

While cracking still residues as shown in the above table can be straight run to a flash point of about 300° F. to prepare them for the blowing, and then blown, and a brittle product obtained, according to this invention it is preferable to mix with the cracking still residues a certain amount of straight run residues, as the final product of such a mixture possesses superior lasting properties in the finished road. Straight running of cracking still residues to about 85° F. M. P. should ordinarily give a safe flash point prior to blowing and give a satisfactory powderable bitumen where cracking still residues are used. Where cracking still residue is used alone, it is not necessary to carry the blowing to as high a melting point as where substantial amounts of straight run residues are mixed therewith in order to produce a hard powderable product. When straight run residue is mixed with cracking still residue, the brittleness of the blown product decreases rapidly, thus requiring more straight run-

ning and requiring blowing to a higher melting point.

With regard to the above examples, it is apparent that they are illustrative merely, for it must be borne in mind that there is practically no uniformity of materials which are ordinarily available for the manufacture of bituminous binders. Not only do the crude oils in different localities differ markedly in their composition and properties, but also refining practices in the removal of the lighter fractions of gasoline, naphtha, kerosene, oils, etc., differ to great extent, so that the residues available for conversion into bituminous binders differ widely in composition. It is a feature of this invention that it is adapted to meet substantially all of these varying conditions in a simple commercial way to produce uniformly satisfactory binders.

The straight reduction residues and cracking still residues which are normally available are often of varying viscosities. In such case, this invention can be appropriately modified in each particular case guided by the following general rules. If the straight run component used in a mixture is of low viscosity, then straight running after mixing to a lesser melting point is required, as the light hydrocarbons are driven off by the straight running, thus increasing the percentage of cracked residues in the remaining material and thus augmenting their effect in making a brittle product. Conversely, if the cracking still residues are of low viscosity, then straight running to a higher temperature is required as the light cracked hydrocarbons are driven off, leaving a lesser concentration of the cracked residues in the remaining material.

In the making of hard bitumen, residues of certain crude oils such as Pennsylvania crudes are unsuitable due to their high paraffin content. Such oils cannot be converted either by blowing or straight distillation to form hard bitumen suitable as a binding material for roads. Those crude oils are preferable which possess a high asphaltic base. Those oils which possess naturally a high naphthene content have been found to give very satisfactory results according to this invention, since they are of such a character that they require less straight running prior to blowing. Thus a satisfactory hard bitumen can be made according to this invention by straight running a high naphthene base crude to a melting point of about 85° F. as a safe flash point is thus obtained and then blowing it to 240-275° F. Moreover, high naphthene base crudes may be mixed with crude residues which give a blown product which is too rubbery or too insoluble or both prior to blowing to increase the powderable quality of the blown product and/or increase its solubility according to this invention.

While this invention has been described as being particularly useful in the production of blown high melting point bitumens which are of increased hardness without sacrificing the solubility of the blown product, it is apparent that this invention can be applied conversely in the production of blown bitumens of increased rubbery quality and/or increased insolubility. Thus by avoiding high naphthene base crudes and cracking still residues and by reducing straight reduction to a minimum prior to blowing, a very rubbery and relatively insoluble product can be obtained if such a product is desired. Where straight run residue is used the blown product is less susceptible to temperature change than blown cracking still residue.

In methods heretofore practiced, difficulties have not only been encountered in securing a satisfactory high melting point bitumen, but also difficulties have been encountered in making and securing relatively low melting point bitumens. Thus in the process of road construction above referred to, the flux oil used should meet the following requirements: The flux oil to be satisfactory should preferably have sufficient viscosity or body properly to coat the aggregate particles at ordinary temperatures, i. e., approximately between 40° F. and 100° F. If the flux is too thin, it will drain off the aggregate particles and coat them insufficiently. A flux which is too thick, on the other hand, does not spread well on the aggregate particles so as to coat them thoroughly and tends to make the mass unworkable unless heating is resorted to with attendant expense and delay. It is preferable to use a flux oil having a viscosity between 600 to 800 sec. Furol, though flux oils which range about 200 sec. Furol above and below the limits above-mentioned may be used, though less advantageously.

In addition to proper viscosity, the flux oil should be of such nature that it will amalgamate at a proper rate with the hard bitumen with which it is used. As herein already stated, the amalgamation should be sufficiently slow to permit the powdered bitumen to remain as a dust adhering to the first coating of the flux oil and keep the aggregate particles from sticking together during handling, shipping, laying, etc., of the mix. The rate of amalgamation should be sufficiently rapid, however, to permit eventually a perfect consolidation and blending by solution of the one binder with the other in the finished road upon rolling and subsequent traffic to produce a composite substantially homogeneous binder of the required specification and melting point.

Heretofore difficulty has been encountered with the use of straight run residues such as fuel oil due to the fact that they lack sufficient solvent power to amalgamate with many hard powdered bitumens without the application of heat.

According to this invention, a flux oil such as fuel oil, which ordinarily is of too low solvent power, can be treated by adding materials thereto which have a relatively high solvent power for hard bitumen to produce a mixture which is satisfactory both in viscosity and solvent power. For example, the solvent property of fuel oil may be increased by adding to it a certain amount of cracking still residues, a material which I have found increases the solvent power of fuel oil when added thereto.

While this invention is not regarded as dependent upon the correctness of any theory which I may advance, I believe that the addition of a substance such as cracking still residues to increase the solvent power of flux oil for high melting point bitumen and therefore the rate at which the two will blend and amalgamate together is due to the fact that cyclic hydrocarbons have high solvent power for hard bitumens and that cracking still residues contain such a large proportion of these cyclic hydrocarbons that the addition of the cracking still residues to the fuel oil causes an increase in the cyclic hydrocarbon content of the resultant mix and a corresponding increase in its solvent power. It is apparent, however, that any other source of cyclic hydrocarbons such as residues from crudes containing naturally a high naphthene content may also be used according to this invention to increase the solvent power of a

flux oil which is deficient in this regard. Moreover, residues from high napthene base crudes may be used alone as a gradual solvent for high melting point bitumens according to this invention. Conversely, where a flux oil possesses too great solvent power and therefore amalgamates too rapidly with a high melting point bitumen, its solvent power may be modified according to this invention by adding to the material a substance which is deficient in cyclic hydrocarbons, such as straight run fuel oil from asphaltic or mixed base crudes, so that the resultant mixture will blend and amalgamate with the hard bitumen at the proper rate. Heretofore differences in cyclic hydrocarbon content and solvent power of residues of different crudes and different refinery processes have not been known or utilized, as herein described and set forth.

Inasmuch as the materials which are available for flux oils differ not only in solvent power but also in viscosity, depending upon the crude oils from which they have been derived and the manner in which the crudes have been treated in making the flux oils, it is apparent the procedure to be followed must be adapted to the materials which are available. The principles which are to be followed according to this invention in selecting a flux oil of proper solvent power have already been set forth above. In order to procure a flux oil which will also have a proper viscosity, a blending of flux oils of different viscosities is frequently required. The production of a flux oil having both a proper solvent power and a proper viscosity is preferably accomplished in a single operation. For example, a flux oil of insufficient solvent power and of too high viscosity may be blended with another oil such as cracking still residues which is of too low viscosity and of too great solvent power, to produce a flux oil which is satisfactory in all respects.

While it is possible to determine the solvent power of a flux oil by actually trying the material out in the manufacture of roads and noting its behavior during mixing and laying and also in the finished road, I have found that a relatively accurate test of the rate of amalgamation of a particular hard bitumen with a particular flux oil may be made in the following way: The hard asphalt is first powdered and that portion which passes a 30 mesh sieve and is retained in a 100 mesh sieve (both U. S. standard sieve series) is combined with the flux at room temperature in such proportion as would give an asphalt cement of 70 penetration at 77° F., 5 secs., 100 grams, if the two were melted together. The materials are then thoroughly mixed and allowed to stand at room temperatures for twenty-four hours, at which time the penetration is taken in the usual manner. The mixture is permitted to stand for an additional six days (one week from the time of mixing) and the penetration again taken. The penetration at the end of a week must be between fifty and eighty per cent. of that at the end of twenty-four hours, for the amalgamation rate to be proper.

From the foregoing, it is apparent that means have been set forth not only for modifying the properties of hard bitumens on the one hand and of flux oils on the other, so that they can be made to correspond to certain specifications and requirements when considered separately, but also for selecting pairs of these materials which blend and amalgamate with each other while cold to produce firm durable binders. This modification and adaptation of the separate flux and

hard bitumen parts so that the two parts may form a pair which co-operate and supplement each other in the most advantageous manner is an important feature of this invention. It is thus possible according to this invention to 80 modify a flux oil so that it may be more advantageously used with a particular hard bitumen and a hard bitumen may also be modified to adapt it for use in conjunction with a particular flux oil. Usually, it is preferable to first modify 85 the properties of the hard bitumen as by increasing both its brittleness and solubility in flux oil and then modify the flux oil so that it will amalgamate perfectly with the bitumen.

The following is a specific illustration of this invention where straight run residues are available which are of about 800 sec. Furol viscosity. As set forth above, where cracking still residues are also available which are of about 400 sec. Furol viscosity, these two materials can be mixed 90 in the proportion of 35 parts of the straight run residues with 65 parts of the cracking still residues, the mixture straight run to a melting point of about 140° F., and then blown to a melting point of 240° F. to 275° F. to produce a hard 95 bitumen which can be readily reduced to a powder and is of increased solubility in flux oil. A flux oil of proper viscosity which will amalgamate with the hard asphalt thus produced may be determined as follows. As it may be assumed 100 for reasons herein stated that straight run residues used alone probably will not dissolve the hard bitumen sufficiently rapidly, a known quantity of the straight run residues may be mixed with a known quantity of cracking still residues 105 to increase its solvent power having in mind also the production of a flux oil of proper viscosity. A test of the rate of fluxing and amalgamation is then made after the manner above described. If the rate of amalgamation is either too rapid 110 or too slow, the original proportions can be changed and the test repeated until flux oil of satisfactory solvent power and viscosity is determined upon. By experiments as above conducted and also by actual use in roads, I have 115 found that a flux oil which will give satisfactory results in connection with the hard bitumen above mentioned will usually have approximately the following composition: 30 parts of straight run residues 800 sec. Furol, 70 parts of 120 cracking still residues 400 sec. Furol.

It is a further feature of this invention that it is applicable not only to the making of relatively low melting point bitumens such as flux oils and the making of relatively high melting point 125 bitumens which are of proper consistency both in themselves and as paired with one another to effect proper amalgamation but that it is also applicable to the making of bituminous materials which will blend and amalgamate as desired with bitumen occurring in bituminous rocks. A bituminous rock, for example, having not only a deficiency of bitumen but also a bitumen of improper consistency for use in road construction may be used in connection with an 130 added bitumen according to this invention so that the rock and added bitumen may merely be mixed together while cold and then laid cold upon the road. Upon subsequent rolling and traffic, a composite consolidated binder can be 135 produced of desired amount and consistency wherein the bitumen occurring naturally in the rock (unsatisfactory in itself) is advantageously utilized by simple means.

Bituminous rock in connection with which 140

this invention is applicable may be any naturally occurring combination of bitumen and mineral such as the bituminous limestones of Alabama and Texas, the bituminous sandstones of Kentucky, the bituminous sands of Alberta and the like. In the usual case, bituminous rocks as mined are unsuitable for paving use due to a deficiency of bitumen and/or due to improper consistency of the bituminous material present. 5

10 Where, for example, a bituminous rock is encountered having a deficiency of bitumen and having a bitumen of too low melting point for use alone in road construction such as Kentucky bituminous sandstone, the bituminous rock may be reduced to desired fineness and powdered bitumen of high melting point coated thereon as an adhering dust which keeps the particles of asphaltic rock separate during mixing but which gradually amalgamates with the bitumen occurring in the rock without the application of heat after laying and upon subsequent rolling and traffic to form a binder proper both in amount and consistency to meet desired specifications. While 15 a hard powderable bitumen of desired solubility in the bitumen occurring in the bituminous rock can be determined by experiment in samples of road, a way of assisting in determining the required hardness, solubility and amount of powdered bitumen to be used in connection with the 20 bitumen in the bituminous rock, is to take a sample of the bituminous rock aggregate used and treat it with a volatile solvent such as benzol to extract the bitumen therefrom. By evaporating the added solvent, a sample of the bitumen occurring in the bituminous rock can be obtained 25 and a determination can be made of the amount thereof which is available for amalgamation with a bituminous coating added thereto. Having obtained a sample of the bitumen occurring in the 30 natural rock, a high melting point bitumen which will have hardness and dissolving power to amalgamate therewith at a desired rate, may be made according to this invention by procedure herein already described in connection with the preparation 35 of hard powderable bitumens which will amalgamate at desired rate with a given flux oil. An amount of powdered bitumen selected in the manner above described is then coated on the aggregate particles, so as to form a composite 40 binder comprising an amalgamation product of the bitumen occurring in the natural rock with the powdered bitumen added thereto which will have a desired melting point for the finished road. If it is desired to build up the total amount of 45 binder in the finished road, a flux oil can be coated upon the aggregate prior to applying the powdered bitumen and then sufficient powdered bitumen added to amalgamate with both the flux oil and with the bitumen occurring in the natural rock. 50 To this end, a flux oil having the proper solvent power for the powdered bitumen may be selected according to methods herein already described. The flux oil used should preferably correspond in 55 solvent power to that of the low melting point bitumen occurring in the natural rock. 60 Where a bituminous rock is available such as Alabama rock asphalt or bituminous limestone having a bitumen content which is deficient and of too high a melting point, an analogous procedure may be employed. In such case the bituminous rock may be reduced to desired fineness and coated with a flux oil in which the hard bitumen in the rock will dissolve and gradually amalgamate without the application of heat. 65 Then a coating of powdered bitumen may be add- 70 ed to keep the aggregate particles separate during mixing and laying and which will gradually amalgamate while cold with the flux oil upon rolling and subsequent traffic. Preferably the exterior coating of powdered bitumen should correspond closely as to solubility with the high melting point bitumen occurring in the bituminous rock. In this case also, the selection of a flux oil which will properly amalgamate with the bitumen occurring in the bituminous rock and of a powderable bitumen which will also amalgamate at proper rate with the flux oil used, may be assisted by extracting with a volatile solvent the bitumen from a sample of the bituminous rock aggregate used, and evaporating the volatile solvent therefrom in order to obtain a sample of the bitumen occurring in the natural rock and determine the amount of bitumen in the aggregate which is available for amalgamating with a coating of flux oil. Having obtained a sample of the bitumen occurring in the rock, a flux oil which will have the proper solvent power and viscosity to pair correctly with the bitumen of the rock can be selected by methods which have already been described in connection with the preparation 75 of a flux oil which will amalgamate at desired rate with a given high melting point bitumen. A powdered asphalt is then selected following procedure already herein disclosed for producing a powdered asphalt which will pair properly with the flux oil. The amount of flux oil and powdered bitumen used may be adjusted in accord with the quantity and melting point of the binder which is desired for the aggregate. 80

melting point and consistency, is regarded as within the scope of this invention.

In the specification and claims, such terms as "high melting point bitumen", "bituminous flux" and the like are to be regarded as embracing both bitumens occurring separately and bitumens occurring in bituminous rocks.

In describing the process of road constructing above referred to wherein a high melting point 10 bitumen, e. g. in powdered form, amalgamates with a bituminous flux without the application of heat, it is understood that the bitumen parts are not heated so as to materially increase the speed at which the two bitumens amalgamate 15 and flux together, as, for example, in hot mix method of road construction wherein bitumen is melted. Where a flux oil chilled as by winter temperatures is warmed slightly merely to decrease its viscosity so that it will flow more readily in pipes leading to a mixer for example and more readily form a coating on the aggregate, the process is to be regarded as being carried out without the application of heat. Where a bituminous flux amalgamates with a high melting 20 point bitumen below about 120° F., the amalgamation is understood to be without the application of heat.

While specific materials and specific figures and proportions have been used in describing this 30 invention, it is to be understood that these have been given for purposes of illustration merely, and that the principles of this invention may be adapted to various other materials and conditions and other figures and proportions without 35 departing from the true scope of this invention. Thus considerable variation in the blending and modifying of constituents, in the extent of straight running, in the extent of blowing and the like may be practiced within the scope of 40 this invention. The figures which have been given are, however, regarded as preferable, both from the practical and economical standpoint and from the standpoint of physical desirability, and furnish an accurate description of and guide to 45 the practice of this invention.

The above-described process of making hard powderable bitumen and product of that process are described and claimed in my divisional application, Serial No. 605,359 filed April 14, 1932.

50 I claim:

1. In a process wherein a solid finely-divided high melting point bitumen is contacted with a fluid flux oil, the flux oil being difficultly soluble with the bitumen without the application of heat, the steps comprising mixing cracking still residue with the flux oil to increase the solvent power of the flux oil for the bitumen and amalgamating the resulting mixture with the solid finely-divided high melting point bitumen without the 55 application of heat.

2. In a process wherein a solid finely-divided high melting point bitumen is contacted with a fluid flux oil, the flux oil being difficultly soluble with the bitumen, the steps comprising increasing the solvent power of the flux oil for the bitumen by adding to it a substance having a higher cyclic hydrocarbon content than said flux oil and amalgamating the solid finely-divided high melting point bitumen with the mixture of 60 flux oil and added substance.

3. In a process wherein a solid finely-divided high melting point bitumen is mixed with a fluid flux oil, the flux oil being capable of amalgamating with the bitumen excessively rapidly, the 75 steps comprising decreasing the solvent power of

the flux oil for the bitumen by adding to it a substance which has a lower cyclic hydrocarbon content than said flux oil and gradually amalgamating the solid high melting point bitumen with the mixture of flux oil and added substance. 80

4. In a process of making a bituminous binder without the application of heat by contacting a powdered bitumen with a flux oil, the step comprising mixing the powdered bitumen with a flux oil consisting substantially of naphthene base 85 crude oil residue.

5. In a process wherein a solid finely-divided high melting point bitumen is contacted with a fluid flux oil, the flux oil being difficultly soluble with the bitumen without the application of heat, the steps comprising mixing naphthene base crude oil residue with the flux oil to increase the solvent power of the flux oil for the bitumen and amalgamating the resulting mixture with the solid finely-divided high melting point bitumen 95 without the application of heat.

6. In a process of making a bituminous binder by preparing a high melting point bitumen in powdered form and gradually amalgamating the powdered bitumen with a bituminous flux without the application of heat, the steps comprising straight running crude residue to a melting point above about 100° F. to form a product which when blown is powderable and gradually soluble without the application of heat in said flux, blowing the thus straight run residue to a high melting point, permitting said blown material to solidify, and powdering said solidified material to form said powdered high melting point bitumen, said powdered high melting point bitumen being thereafter amalgamated without the application of heat with said flux.

7. In a process of making a bituminous binder by preparing a high melting point bitumen in powdered form and gradually amalgamating the powdered bitumen with a bituminous flux without the application of heat, the steps comprising blowing bitumen comprising cracking still residue to a high melting point, permitting said high melting point bitumen to solidify, and powdering said solidified material to form said powdered high melting point bitumen; said powdered high melting point bitumen being thereafter amalgamated with said flux without the application of heat. 125

8. In a process of making a bituminous binder by preparing high melting point bitumen in powdered form and gradually amalgamating the powdered bitumen with a bituminous flux without the application of heat, the steps comprising blowing bitumen comprising naphthene base residue to a high melting point, permitting said high melting point bitumen to solidify, and powdering said solidified material to form said powdered high melting-point bitumen, said powdered high melting-point bitumen being thereafter amalgamated with said flux without the application of heat.

9. In a process of making a bituminous binder for aggregate by preparing a high melting point 140 bitumen in powdered form and a flux oil and contacting the bituminous flux with the powdered bitumen as a binder coating for the aggregate, the steps comprising straight running crude residue to rid same of hydrocarbons which are relatively insoluble and rubbery when blown, blowing the residue thus straight run to a high melting point, allowing the high melting point bitumen to solidify, powdering said high melting point bitumen, and amalgamating said high melt- 145

- ing point bitumen with the flux oil, said flux oil containing a portion of straight run residue and a portion of cracking still residue.
10. In a process of making a bituminous binder for aggregate by preparing a high melting point bitumen in powdered form and a flux oil and contacting the bituminous flux with the powdered bitumen as a binder coating for the aggregate, the steps comprising straight running crude residue to rid same of hydrocarbons which are relatively insoluble and rubbery when blown, blowing the residue thus straight run to a high melting point, allowing the high melting point bitumen to solidify, powdering said high melting point bitumen, and amalgamating as a substantially homogeneous composite binder for the aggregate without the application of heat said powdered high melting point bitumen with said flux oil, said flux oil containing a portion which is difficultly soluble with said powdered high melting point bitumen and to which has been added a substance having a higher cyclic hydrocarbon content than said difficultly soluble portion.
11. In a process of making a bituminous binder for aggregate by preparing a high melting point bitumen in powdered form and a flux oil and contacting the powdered bitumen with the bituminous flux as a binder coating for the aggregate, the steps comprising straight running a mixture of straight run residue and cracking still residue to rid same of substances which are relatively insoluble and rubbery when blown, blowing the mixture to a high melting point, allowing the high melting point bitumen to solidify, powdering said high melting point bitumen, and amalgamating said high melting point bitumen with flux oil, said flux oil containing a portion of straight run residue and a portion of cracking still residue.
12. In a process of making a bituminous binder for aggregate by preparing a high melting point bitumen in powdered form and a flux oil and contacting the powdered bitumen with the bituminous flux as a binder coating for the aggregate, the steps comprising straight running a mixture of straight run residue and cracking still residue to rid same of substances which are relatively insoluble and rubbery when blown, blowing the mixture to a high melting point, allowing the high melting point bitumen to solidify, powdering said high melting point bitumen, and amalgamating as a substantially homogeneous composite binder for the aggregate without the application of heat said powdered high melting point bitumen with said flux oil, said flux oil containing a portion which is difficultly soluble with said powdered high melting point bitumen and to which has been added a substance having a higher cyclic hydrocarbon content than said difficultly soluble portion.
13. In a process of making a bituminous binder for aggregate by preparing a high melting point bitumen in powdered form and a flux oil and contacting the bituminous flux with the powdered bitumen as a binder coating for the aggregate, the steps comprising blowing cracking still residue to a high melting point, allowing said high melting point bitumen to solidify, powdering said high melting point bitumen, and amalgamating as a substantially homogeneous composite binder for the aggregate without the application of heat said powdered high melting point bitumen with the flux oil, said flux oil containing a portion of straight run residue and a portion of cracking still residue.
14. In a process of making a bituminous binder for aggregate by preparing a high melting point bitumen in powdered form and a flux oil and contacting the bituminous flux with the powdered bitumen as a binder coating for the aggregate, the steps comprising blowing cracking still residue to a high melting point, allowing said high melting point bitumen to solidify, powdering said high melting point bitumen, and amalgamating as a substantially homogeneous composite binder for the aggregate said powdered high melting point bitumen with said flux oil, said flux oil containing a portion which is difficultly soluble with said powdered high melting point bitumen and to which has been added a substance having a higher cyclic hydrocarbon content than said difficultly soluble portion.
15. In a process of making a bituminous binder for aggregate by preparing a high melting point bitumen in powdered form and a flux oil and contacting the bituminous flux with the powdered bitumen as a binder coating for the aggregate, the steps comprising blowing naphthene base crude residue to a high melting point, allowing said high melting point bitumen to solidify, powdering said high melting point bitumen, and amalgamating said high melting point bitumen with the flux oil, said flux oil containing a portion of straight run residue and a portion of cracking still residue.
16. As a composite binder for aggregate a powdered high melting point bitumen amalgamated without the application of heat with a mixture of straight run residue and cracking still residue.
17. As a composite binder for aggregate a powdered high melting point bitumen amalgamated without the application of heat with naphthene base crude oil residue.
18. As a composite binder for aggregate a powdered high melting point bitumen amalgamated without the application of heat with naphthene base crude oil residue mixed with crude residue of less solvent power.
19. In a process wherein a bituminous rock is coated with a flux oil which is excessively resistant while relatively cold to amalgamation with bitumen occurring in said bituminous rock, the steps comprising mixing cracking still residue with said flux oil to increase the solvent power thereof for the bitumen occurring in the bituminous rock and amalgamating the bitumen in the bituminous rock with said mixed flux oil and cracking still residue while the same are relatively cold.
20. In a process wherein a bituminous rock is coated with a flux oil which is excessively resistant while relatively cold to amalgamation with bitumen occurring in said bituminous rock, the steps comprising mixing a naphthene base crude oil residue with said flux oil to increase the solvent power thereof for the bitumen occurring in the bituminous rock and amalgamating the bitumen in the bituminous rock with said mixed flux oil and naphthene base crude oil residue while the same are relatively cold.
21. A process wherein a bituminous rock is coated with a bituminous flux oil comprising naphthene base crude oil residue as a gradual fluxing oil for bitumen occurring in the bituminous rock, said fluxing occurring without the application of heat.
22. A process wherein a bituminous rock is coated with a bituminous flux oil comprising cracking still residue as a gradual fluxing oil for

bitumen occurring in bituminous rock, said fluxing occurring without the application of heat.

23. A process of making a consolidated bituminous binder for aggregate material comprising 5 bituminous rock, said process comprising applying to the aggregate a flux oil modified so as to gradually amalgamate without the application of heat with the bitumen occurring in the bituminous rock by adjusting the cyclic hydrocarbon 10 content thereof, and applying to the aggregate thus coated a powdered high melting point bitumen which gradually amalgamates with said flux oil without the application of heat.

24. In a process of coating aggregate with a 15 bituminous binder, said aggregate comprising bituminous rock containing bitumen having a melting point lower than is necessary to resist summer heat and said process including the application of powdered asphalt as a coating to said aggregate, the steps comprising coating said aggregate with an adhering dust of powdered bitumen having a melting point higher than is necessary to resist summer heat and adapted to amalgamate without the application of heat with bitumen occurring in the bituminous rock, said dust 25 of powdered bitumen without the application of heat forming with the bitumen naturally occurring in said bituminous rock an amalgamated binder having a melting point sufficiently high to 30 resist summer heat.

25. A process of coating with bituminous binder aggregate material comprising bituminous rock containing bitumen having a melting point higher than is necessary to resist summer heat, said 35 process comprising coating said aggregate with flux oil having a melting point lower than is necessary to resist summer heat and adapted to amalgamate without the application of heat with bitumen occurring in the bituminous rock, and 40 then applying an exterior coating of powdered bitumen having a melting point higher than is necessary to resist summer heat which adheres to said first coating of flux oil as a dust and which is adapted to gradually amalgamate without the 45 application of heat with said flux oil producing an amalgamated binder having a melting point sufficiently high to resist summer heat.

26. A process of coating aggregate material comprising bituminous rock with a composite bituminous binder having a melting point sufficiently high to resist summer heat, said process comprising applying to said aggregate a coating of flux oil adapted to amalgamate without the application of heat with bitumen occurring in 55 the bituminous rock, and then applying an exterior coating of powdered bitumen having a melting point higher than is necessary to resist summer heat which adheres to said first coating of flux oil as a dust and which is adapted to gradually amalgamate without the application of heat with said flux oil producing an amalgamated binder having a melting point sufficiently high to 60 resist summer heat.

27. A process of making a material for roads 65 comprising coating particles of aggregate comprising bituminous rock with an adhering dust-like coating of powdered bitumen, which coating separates the particles of aggregate from each other during mixing and laying and is adapted 70 to amalgamate without the application of heat upon consolidation of the mass in place with bitumen occurring in the rock to produce a binder having a melting point sufficiently high to resist summer heat.

28. A process of making a material for roads

comprising coating particles of aggregate comprising bituminous rock with a flux oil adapted to gradually amalgamate without the application of heat with bitumen occurring in the bituminous rock and applying to the aggregate a second dust-like coating of powdered bitumen adhering to the first coating as a dust which separates the aggregate particles during mixing and laying and is adapted to gradually amalgamate with the first coating without the application of heat to produce a binder having a melting point sufficiently high to resist summer heat.

29. In a process of coating aggregate material with a bituminous binder wherein a powdered high melting-point binder is prepared and is mixed with a flux oil as a composite binder coating for the aggregate, the aggregate with said coating thereon being thereafter consolidated in place and both said mixing and consolidating being without application of heat, the steps comprising straight running crude residue to a melting-point above about 100° F. to rid same of hydrocarbons which are relatively insoluble and rubbery when blown, blowing the material to a high melting-point, allowing the blown material to 100 solidify, powdering the solidified material, and increasing the solvent power of a flux oil for said powdered high melting-point bitumen by adding to said flux oil a substance having a higher cyclic hydrocarbon content than said flux oil, said 105 powdered bitumen part and flux oil part then being mixed and consolidated as aforesaid thereby amalgamating said parts.

30. In a process of coating aggregate material with a bituminous binder wherein a powdered high melting-point binder is prepared and is mixed with a flux oil as a composite bonder coating for the aggregate, the aggregate with said coating thereon being thereafter consolidated in place and both said mixing and consolidating being without application of heat, the steps comprising straight running crude residue to a melting-point above about 100° F. to rid same of hydrocarbons which are relatively insoluble and rubbery when blown, blowing the material to a 110 high melting point, allowing the blown material to solidify, powdering the solidified material, and decreasing the solvent power of a flux oil for said powdered high melting point bitumen by adding to said flux oil a substance having a lower cyclic 115 hydrocarbon content than said flux oil, said powdered part and flux oil part then being mixed and consolidated as aforesaid, thereby amalgamating said parts.

31. In a process of coating aggregate material with a bituminous binder wherein a powdered high melting-point bitumen is prepared and is mixed with a flux oil as a composite binder coating for the aggregate, the aggregate being thereafter consolidated in place and both said mixing 135 and said consolidating being without the application of heat, the steps comprising blowing crude residue comprising cracking still residue to a high melting point, allowing the blown high melting point bitumen thus made to solidify, powdering 140 said solidified high melting-point bitumen, and increasing the solvent power of said flux oil for said powdered high melting-point bitumen by adding to said flux oil a substance having a higher cyclic hydrocarbon content than said flux oil, 145 said powdered bitumen part and flux oil part then being mixed and consolidated as aforesaid, thereby amalgamating said parts.

32. In a process of coating aggregate material with a bituminous binder wherein a powdered

- high melting-point bitumen is prepared and is mixed with a flux oil as a composite binder coating for the aggregate, the aggregate being thereafter consolidated in place and both said mixing 5 and said consolidating being without the application of heat, the steps comprising blowing crude residue comprising cracking still residue to a high melting-point, allowing the blown high melting-point bitumen thus made to solidify, 10 powdering said solidified high melting-point bitumen, and decreasing the solvent power of a flux oil for said high melting point bitumen by adding to said flux oil a substance having a lower cyclic hydrocarbon content than said flux oil, said powdered bitumen part and flux oil part being mixed 15 and consolidated as aforesaid, thereby amalgamating said parts.
33. In a process of coating aggregate material with a bituminous binder wherein a powdered high melting point binder is prepared and is mixed with a flux oil as a composite binder coating for the aggregate, the aggregate with said coating thereon being thereafter consolidated in place and both said mixing and consolidating 20 being without application of heat, the steps comprising blowing crude residue comprising naphthalene base crude residue to a high melting-point, allowing the blown high melting-point bitumen thus made to solidify, powdering said high melting-point bitumen, and increasing the solvent power of a flux oil for said powdered high melting-point bitumen by adding to said flux oil a substance having a higher cyclic hydrocarbon content than said flux oil, said powdered bitumen 25 part and flux oil part then being mixed and consolidated as aforesaid, thereby amalgamating said parts.
34. In a process of coating aggregate material with a bituminous binder wherein a powdered high melting-point binder is prepared and is mixed with a flux oil as a composite binder coating for the aggregate, the aggregate with said coating thereon being thereafter consolidated in place and both the mixing and consolidating being 30 without application of heat, the steps comprising blowing crude residue comprising naphthalene base crude residue to a high melting-point, allowing the blown high melting-point bitumen thus made to solidify, powdering said high melting-point bitumen, and decreasing the solvent powder of said flux oil for said powdered high melting-point bitumen by adding to said flux oil a substance having a lower cyclic hydrocarbon content than said flux oil, said powdered part and flux oil part then being mixed and consolidated 35 as aforesaid; thereby amalgamating said parts.
35. In a process of coating aggregate material with a bituminous binder wherein a powdered high melting-point binder is prepared and is mixed with a flux oil as a composite binder coating for the aggregate, the aggregate with said coating thereon being thereafter consolidated in place, both said mixing and consolidating being without the application of heat, the steps comprising blowing crude residue to a high melting-point, allowing the high melting-point bitumen thus made to solidify, powdering said high melting-point bitumen and increasing the solvent power of a flux oil for said powdered high melting-point bitumen by adding to said flux oil a substance having a higher cyclic hydrocarbon content than said flux oil, said powdered bitumen part and flux oil part then being mixed and consolidated as aforesaid, thereby amalgamating 40 said parts.
36. In a process of coating aggregate material with a bituminous binder wherein a powdered high melting-point binder is prepared and is mixed with a flux oil as a composite binder coating for the aggregate, the aggregate with said coating thereon being thereafter consolidated in place, both said mixing and consolidating being without the application of heat, the steps comprising blowing crude residue to a high melting-point, allowing the high melting-point bitumen thus made to solidify, powdering said high melting-point bitumen and decreasing the solvent power of said flux oil for said powdered high melting-point bitumen by adding to said flux oil a substance having a lower cyclic hydrocarbon content than said flux oil, said powdered part and flux oil part then being mixed and consolidated as aforesaid, thereby amalgamating said parts.
37. In a process of coating aggregate with a bituminous binder, said aggregate material comprising bituminous rock containing naturally-occurring bituminous flux, wherein a powdered high melting point bitumen is employed, the steps comprising preparing a high melting point bitumen which will amalgamate with the bituminous flux naturally occurring in the bituminous rock by blowing crude residue which has been straight run to a melting point above 100° F. prior to blowing to form a product which when blown is powdery and has a high melting point, and powdering said high melting-point bitumen, said powdered high melting-point bitumen thereafter being amalgamated with the bituminous flux naturally occurring in said bituminous rock to form a composite binder for said aggregate.
38. In a process of coating aggregate with a bituminous binder, said aggregate comprising bituminous rock containing naturally-occurring bituminous flux, wherein a powdered high melting-point bitumen is employed, the steps comprising preparing a high melting-point bitumen which will amalgamate with the bituminous flux naturally occurring in said bituminous rock by blowing crude residue which has been mixed with cracking still residue prior to blowing to a high melting-point, and powdering the high melting-point bitumen, the said powdered high melting-point bitumen thereafter being amalgamated with the bituminous flux naturally occurring in said bituminous rock to form a composite binder for the aggregate.
39. In a process of coating aggregate with a bituminous binder, said aggregate comprising bituminous rock containing naturally-occurring bituminous flux, wherein a powdered high melting-point bitumen is employed, the steps comprising preparing a high melting point bitumen by blowing crude residue which has been mixed with naphthalene base crude residue prior to blowing to a high melting point and powdering the high melting point bitumen thus preparing, said powdered high melting point bitumen thereafter being amalgamated with the bituminous flux naturally occurring in said bituminous rock to form a composite binder for the aggregate.
40. In a process of coating aggregate with a bituminous binder, said aggregate comprising bituminous rock containing naturally-occurring bituminous flux, wherein a powdered high melting-point bitumen is employed, the steps comprising preparing a high melting-point bitumen which will flux with the bituminous flux naturally occurring in said bituminous rock by blowing to high melting point crude residue which prior to blowing has been mixed with cracking still resi-

- due and which prior to blowing has been straight run to rid same of substances which when blown are rubbery and relatively insoluble in the bituminous flux naturally occurring in said bituminous rock, and powdering the high melting-point bitumen, said high melting-point bitumen thus prepared being thereafter amalgamated with said bituminous flux naturally occurring in said bituminous rock as a composite binder for the aggregate.
41. In a process of coating aggregate with bituminous binder, said aggregate comprising bituminous rock containing naturally-occurring bituminous flux, wherein a powdered high melting point bitumen is employed, the steps comprising preparing a high melting-point bitumen which will flux with the bituminous flux naturally occurring in said bituminous rock by blowing cracking still residue to a high melting-point, and powdering the high melting-point bitumen thus produced, the powdered high melting-point bitu-

men thus prepared thereafter being amalgamated with the bituminous flux naturally occurring in said bituminous rock as a composite binder for the aggregate.

42. In a process of coating aggregate with a bituminous binder, said aggregate comprising bituminous rock containing naturally-occurring bituminous flux, wherein a powdered high melting-point bitumen is employed, the steps comprising preparing a powdered high melting-point bitumen which will flux with the bituminous flux naturally occurring in said bituminous rock by blowing naphthene base crude residue to a high melting-point, and powdering the high melting-point bitumen thus produced, the high melting-point bitumen thus prepared thereafter being amalgamated with the bituminous flux naturally occurring in said bituminous rock to produce a composite binder for the aggregate.
